UNITED STATES PATENT OFFICE.

HOWARD A. STOFFLET, OF READING, PENNSYLVANIA.

GALVANIC CELL.

1,285,831.

Specification of Letters Patent. Patented Nov. 26, 1918.

Application filed November 22, 1916. Serial No. 132,901.

To all whom it may concern:

Be it known that I, HOWARD A. STOFFLET, a citizen of the United States, residing at Reading, in the county of Berks and State 5 of Pennsylvania, have invented certain new and useful Improvements in Galvanic Cells, of which the following is a specification.

My invention relates particularly to galvanic cells for primary batteries; and it consists in providing in connection with an element receptacle, which is preferably independently removable from the jacket, an inclosing receptacle through which and its contents the electrolytic liquid passes to said 15 element, as described in connection with the accompanying drawings and defined in the subjoined claims.

Figure 1 is a side elevation of a cell embodying my complete invention in preferred 20 form, the jacket being shown in cross-section on the line 1—1 of Fig. 2; and dotted lines indicating a partially withdrawn position of the independently removable receptacle.

Fig. 2 is a cross-sectional view on the line 25 2—2 of Fig. 1, the partially withdrawn position of the independently removable receptacle being again indicated by dotted lines.

Fig. 3 is a sectional plan view on the line 30 3—3 of Fig. 2.

Fig. 4 is a sectional perspective view of the independently removable receptacle.

Figs. 5 and 6 indicate a modified construction, Fig. 5 being a horizontal section on the line 5—5 of Fig. 6, and Fig. 6 a sectional 35 view on the line 6—6 of Fig. 5.

Figs. 1 to 4 illustrate a jacket or jar 7 of rectangular form, while Figs. 5 and 6 show a cylindrical jacket 7^a; the parts contained therein being shown correspondingly 40 varied in shape. Figs. 1 to 4 only show the preferred construction, in which the central receptacle is adapted for convenient removal to permit of independently renewing its contained element.

The use of a comminuted depolarizing element greatly increases the galvanic action, and the main purpose of my invention is to provide for satisfactorily employing an element in such form. To this end I provide a 45 central receptacle 8 having perforate walls 9, for the comminuted material, in connection with an inclosing receptacle 10 having perforate walls, for a suitable intercepting material, the latter being adapted to permit the 50 passage of the electrolytic liquid there-

through to the comminuted element while at the same time serving to practically retain the latter in its receptacle. I preferably fill this receptacle 8 with powdered black copper oxid, and the inclosing receptacle 10 with exhausted copper flake, which materials I find to coöperate very satisfactorily for the 60 securing of the desired results.

The jacket 7, as shown, is provided with an insulating cover plate 15 to which both 65 the positive element, as zinc plates 16, 16, and the inclosing receptacle 10 of the negative element, are secured, together with binding posts 17, 17, 18, 18, for the usual connecting wires; the receptacle 8 being separately formed and independently insertible 70 through a cover-plate aperture 20 having a removable cap 21.

As shown, the receptacle 8 has the shape of a deep rectangular box, is formed of finely 75 perforated sheet metal, and open at the top for filling in or emptying the comminuted material. The inclosing receptacle 10 is likewise formed mainly of perforated sheet metal; with duplicate compartments, 25, 25, 80 of rectangular cross-section, each having (see Fig. 3) an inner perforate wall 26 and an outer perforate wall 27 spaced apart by vertical wall-bars 28, 28, and said compartments being spaced apart by similar wall-bars 29, 29 to form between them a central 85 compartment into which the receptacle 8 is removably inserted. The zinc plates 16, 16, are, as indicated, carried by insulating brackets 31, 31, 31, 31, on the outer walls of 90 the receptacle 10, while the latter is fixed to depending brackets 32, 32 on the cover plate.

The electrolytic liquid, as caustic soda or potash, comes into contact with the comminuted copper oxid or equivalent material 95 in the central receptacle 8, by passing through the intercepting material in the inclosing receptacle 10; the term intercepting being employed to define the essential function of said inclosing material, namely the 100 retaining of the comminuted material in receptacle 8 while at the same time permitting the energetic galvanic action incident to its comminuted form. Renewal of this comminuted material is most conveniently provided for by means of the independently removable receptacle 8, as described, and the 105 general construction is simple and economical. In the modification shown in Figs. 5 and 6, previously referred to, the main fea- 110

tures of my invention are retained, the receptacle 8^a however being rigidly combined with the inclosing receptacle 10^a and removable with the latter through the cover plate aperture, but without disturbing the zinc-element connections.

What I claim is:—

1. In a galvanic cell employing an electrolytic liquid and a comminuted element; a 10 separately insertible and removable receptacle for the latter having perforate walls, and a relatively fixed inclosure for said inserted receptacle having walls impermeable by said comminuted element but permeable by the electrolytic liquid.
2. In a galvanic cell employing an electrolytic liquid and a comminuted element; a 15 separately insertible and removable receptacle for the latter having perforate walls, and a relatively fixed inclosure for said inserted receptacle having double perforate walls forming an inclosing receptacle; the latter containing an intercepting material adapted

to retain the comminuted element and to permit passage of the electrolytic liquid thereto. 25

3. A galvanic cell comprising a jacket having a cover plate provided with a central aperture, an outer element and an inclosing receptacle fixed to said cover plate, and a separate central receptacle insertible through 30 said aperture; the walls of both said receptacles being perforate to permit passage of the electrolytic fluid through said inclosing receptacle into said central receptacle.

4. A galvanic cell comprising a jacket having a cover plate provided with an aperture, an outer-element carried by said cover plate, and a central-element receptacle inclosed by a receptacle for intercepting-material also carried by said cover plate; said central-element receptacle being removable through said aperture without disturbing said outer-element. 35 40

In testimony whereof I affix my signature.

HOWARD A. STOFFLET.
